TOY CONSTRUCTION PIECE

Robert A. Wolfe, 455 Elizabeth Ave., Newark, N.J.

Filed June 30, 1964, Ser. No. 80,646

Term of patent 14 years

(D34—15)

FIG. 1 is a top plan view of a toy construction piece, showing my new design, wherein the piece is wedge-shaped having concave and convex ends in order to form a curved portion of a trough-like track;

FIG. 2 is a bottom plan view thereof;

FIG. 3 is an edge view thereof;

FIG. 4 is a top plan view wherein the toy construction piece is square in shape in order to form a straight portion of a trough-like track; and

FIG. 5 is a bottom plan view thereof.

I claim:

The ornamental design for a toy construction piece, substantially as shown and described.
